United States Patent

Des. 242,481
Patented Nov. 23, 1976

242,481

TOY FIRE STATION

Robert M. Farmer, 505 Harrison Drive,
Wilson, N.C. 27893

Filed Oct. 16, 1974, Ser. No. 515,233

Term of patent 14 years

Int. Cl. D21—01

U.S. Cl. D34—15 LL

FIG. 2

FIG. 1

FIG. 3

FIG. 4

FIG. 1 is a front perspective view of a toy fire station showing my new design;

FIG. 2 is a front elevational view thereof shown on a slightly reduced scale with the front doors in a closed condition;

FIG. 3 is a top plan view thereof; and

FIG. 4 is a rear elevational view thereof, with the rear door in an open condition.

The bottom of the design is substantially plain and unornamented.

I claim:

The ornamental design for a toy fire station, as shown and described.
